United States Patent Office

Des. 177,629
Patented May 8, 1956

177,629

ADVERTISING SIGN

Harry L. Jones, Houston, Tex.

Application November 8, 1954, Serial No. 33,023

Term of patent 3½ years

(Cl. D1—12)

Fig. 1 is a front elevational view of an advertising sign embodying my design;

Fig. 2 is a right-side elevational view thereof; and
Fig. 3 is a left-side elevational view thereof.

What is claimed is:

The ornamental design for an advertising sign, substantially as shown.
